UNITED STATES PATENT OFFICE.

GEORGE J. HUDSON, OF DALLAS, TEXAS.

COLLAR FASTENER AND SUPPORTER.

1,384,956.

Specification of Letters Patent. Patented July 19, 1921.

Application filed March 29, 1921. Serial No. 456,553.

To all whom it may concern:

Be it known that I, GEORGE J. HUDSON, a citizen of the United States, residing at Dallas, in the county of Dallas and State of Texas, have invented certain new and useful Improvements in Collar Fasteners and Supporters, of which the following is a specification.

This invention relates to new and useful improvements in collar fasteners and supporters.

The object of the invention is to provide a supporter which may be readily attached to the collar and at the same time concealed. A further object is to provide a supporter having two members which are adapted to be hooked together so as to properly hold the front of the collar in position. A still further object is to make the supporter in a simple and inexpensive manner which will permit of a general use.

In carrying out the invention the supporter is constructed of two members, each of which is formed with a staff provided with a loop and an extending arm. The loop has a particular function in providing a resilient member which clamps the fabric to the staff, whereby the staff is retained in position.

A construction designed to carry out the invention will be hereinafter described together with other features of the invention.

The invention will be more readily understood from a reading of the following specification and by reference to the accompanying drawings, in which an example of the invention is shown and wherein:

Figure 1 is an elevation of one of the members of the supporter embodying the invention,

Fig. 2 is an elevation of the other member, Fig. 3 is a front elevation of a collar showing the fastening members in position thereon,

Fig. 4 is a detail showing one of the members as it engages the inner side of the front flap of a collar,

Fig. 5 is an elevation of a modified form, and

Fig. 6 is an elevation of the member used with that shown in Fig. 5.

In the drawings the numeral 10 designates a staff which may have a blunt point 11 at its lower end. The staff is bent upon itself at its upper end to form a loop 12. A laterally directed arm 13 extends from

each loop. The lower end of each loop is bent inwardly so as to engage the side of the staff. The staffs are made in pairs to form supporting members and the arm 13 of one is provided with a downturned hook 14, while the arm 13 of the corresponding member is provided with a horizontal eye 15 adapted to receive said hook.

In the drawing I have shown a soft collar having the usual down-turned flap A and the inner upright neckband B to which the flap is attached. The flap A is always made of several layers of cloth. In using my collar supporter the staff 10 is pushed into the flap A by penetrating the inner layer of cloth with the point 11, so that the staff does not penetrate the front layer but is concealed within said flap. In inserting the staff it is started near the front edge of the flap and at a point below the fold at the top of the flap. The location will depend somewhat upon the nature of the necktie. If the necktie is heavy and makes a large knot the staff will have to be placed lower down on the flap than where a small tie is used.

It will be noticed that when the staff is inserted into the goods, said goods will be clamped between the lower end of the loop and the side of the staff as is clearly shown in Fig. 4, thereby preventing upward displacement of the member. It is preferable to make the members of resilient material. The arms 13 are bent downwardly so that when the hook 14 is engaged in the eye 15 said arms will form an obtuse angle under the knot of the necktie, thereby giving ample room for the same which would not be had if the arms extended straight across the collar as will be evident from Fig. 3. When the arms are hooked together the front edges of the collar will be connected and the staffs will support the front edges so as to lend a neat appearance as will be obvious.

Under some conditions it would be necessary to provide an adjustment of the front edges of the flap A, and for this purpose I have shown a modification in Figs. 5 and 6. In these figures the loops 12 each terminate in a laterally directed eye 16. A small coiled spring 17 is fastened to one of the eyes and provided with a hook 18 at its opposite end which is engaged in the eye 16 of the other member. This arrangement permits the front edges of the collar to be spread apart and would be particularly useful in connection with a necktie which tied in a large

knot or a collar which had flaring front edges.

The supporter members may be made of any suitable material and may be made of flat or round wire or the like. The supporters may be used as found best by the individual wearer and may be inserted to suit the fancy of the person using them. It is pointed out that each member may be made 10 of a single piece of wire quickly bent into shape and cheaply produced.

Various changes and modifications may be made without departing from the spirit of the invention.

15 What I claim, is:

1. In a collar supporter, a pair of members each comprising a staff with a blunt point and having a clamping loop at its upper end, a laterally extending arm carried by each 20 loop, and means for fastening the arms together.

2. In a collar supporter, a pair of staffs,

each having a blunt point at one end and a clamping loop at the other end, and connecting means detachably engaging between 25 the loops.

3. In a collar supporter, a pair of resilient members each comprising a staff having a point at one end and a loop at the other end, each of said loops having its lower end in 30 engagement with the side of the staff and forming a clamp for engaging the fabric of the collar, and connecting means between the loops.

4. In a collar supporter, a pair of staffs, 35 each staff having one end adapted for insertion within the material of the flap of a soft collar or the like near the free edge of the flap, said staff being provided near its opposite end with a clamping loop, and 40 means for connecting said loops.

In testimony whereof I affix my signature.

GEORGE J. HUDSON.
